UNITED STATES PATENT OFFICE.

JOHN HICKS, OF CALGARY, ALBERTA, CANADA.

GAS-BURNER.

1,233,779.

Specification of Letters Patent. Patented July 17, 1917.

Application filed April 3, 1917. Serial No. 159,513.

To all whom it may concern:

Be it known that I, JOHN HICKS, a subject of the King of Great Britain, residing at Calgary, in the Province of Alberta and 5 Dominion of Canada, have invented new and useful Improvements in Gas-Burners, of which the following is a specification.

This invention relates to certain improvements on my former application, allowed 10 January 9, 1917, and bearing Serial Number 58,288. It is the object of this invention to provide a gas burner of the vertical type, primarily intended for use with gas furnaces, and which is exceedingly simple in 15 construction and compact, producing a heat of great intensity consistent with the consumption of a minimum amount of fuel.

The nature and advantages of the invention will be better understood when the following detail description is read in connection with the accompanying drawing, the invention residing in the construction, combination and arrangement of parts as claimed.

25 In the drawing forming part of this specification like numerals of reference indicate similar parts in the several views and wherein:

Figure 1 is a vertical sectional view 30 through the preferred form of the invention.

Fig. 2 is a similar view of a modified form of the invention.

Fig. 3 is a transverse sectional view 35 through the annulus showing the angular disposition of the perforations.

Referring more particularly to the drawing in detail, 10 indicates a hollow body open at both ends, and constituting an air 40 tube and mixing chamber. The body 10 may be tapered or of any desired proportion, without departing from the spirit of the invention, and as illustrated the body is offset at 11 to provide a relatively large end portion. The body 10 is adapted to be vertically disposed, and is supported by means of one or more legs 12 which by preference is separable from the body 10, but secured thereto in any suitable manner, as for instance through the instrumentality of the 45 screw fastening 13. It is of course to be understood that if desired this leg 12 may form an integral part of the body.

Removably fitted within the enlarged end 50 portion of the body as shown, is a hollow

annulus 14 of a size to snugly fit within the enlarged end portion of the body, and provided with a circumferential series of openings 15 adjacent its uppermost extremity, and which openings are disposed tangentially to the axis of the body 10. A gas supply pipe 16 communicates with the hollow annulus, preferably having one extremity threaded through a boss 17 and the wall of the body 10, this extremity of the pipe being 60 also threaded into the outer wall of the annulus 14. Supported by the body 10 at a suitable point in its circumference, is a set screw 18 which bears against the annulus 14 and co-operates with the pipe 16 in supporting 65 the annulus within the body 10. Depending from the lower edge of the body is a set screw 19 which supports a swingingly mounted shutter 20 which controls the admittance of air into the tube from the lower 70 extremity thereof, the shutter being disposed to swing across this lower open end of the tube as shown.

Projecting inwardly from the inner wall of the annulus at an appropriate point in its 75 circumference, and also adjacent the lower end thereof, is a horizontally disposed pipe 21 communicating with the space between the concentrically disposed walls of the annulus, and terminating to provide a vertically disposed portion 22. Detachably associated with the vertical portion 22 of the pipe is a perforated cap 23, the perforations of which are disposed at an angle so that the streams of gas from these perforations will 80 be directed upwardly and outwardly in a diagonal course, to strike against the inner 85 wall of the annulus 14.

In practice, the valve 24 in the supply pipe 16 is open, and the gas passes therefrom into the hollow annulus 14, a portion 90 of this gas passing therefrom through the openings 15 adjacent the upper edge of the annulus, while a portion of the gas passes through the pipe 21, from which it passes 95 in streams through the perforations of the cap 23, and directed in the manner above stated against the inner wall of the annulus. The rush of gas through the hollow body 10 draws the air through the lower open end 100 of the body to mix with the ingoing streams of gas to form a perfect combustible mixture. It will be noted from the disclosure that the streams of gas passing from the 105 perforated cap 23 takes the air with it, these 110

streams striking the inner wall of the annulus approximately one-fourth of an inch below the openings 15. The streams of gas and air from the perforated cap 23 rebound 5 from the inner wall of the annulus toward the center of the body 10, and smashes itself into a fine combustible mixture. Before this mixture can separate, it is taken up by the rotary motion of the gas passing into 10 the body 10 through the openings 15 which are tangentially disposed with respect to the axis of the body for this purpose. The air and gas are thus held together while 15 passing through the body 10 in a whirling motion to the point of ignition, thus making the most perfect combustible mixture obtainable and producing a great heat intensity. It is manifest, that by reason of the construction and contemplated operation, that the burner at all times is 20 completely filled, the result being the provision of a better flame and more speed than is obtainable in burners of this character.

In Fig. 2 I have disclosed a modified form 25 of the invention, which differs from the preferred form only in the respect that the air tube and mixing chamber is made up of the sections 25 and 26 respectively, which are slid together and held fixed relatively in 30 any suitable manner, preferably by means of the threaded element 27. In this instance the hollow annulus 28 is slightly wider than the space between the sections 25 and 26 at the point where these sections overlap, so 35 that the annulus forms a support for the section 25 of the air tube and mixing chamber. The section 26 has integrally formed therewith a supporting leg 29, although this may be separable, and detachably secured 40 to the section 26 in the manner hereinabove described for connecting the leg 12 to the body 10. In other respects this form of the invention, and the principle of operation is 45 exactly the same as that hereinabove described in connection with the preferred form of the invention.

While I have shown and described what I consider the best forms of the invention, I desire to have it understood that I do not 50 limit myself to this precise construction and arrangement of parts, and that such changes may be resorted to when desired as fall within the scope of what is claimed.

What is claimed is:—

1. A gas burner comprising a hollow body 55 open at both ends and constituting an air tube and mixing chamber, means for supporting said tube vertically, a hollow annulus fitted within said tube adjacent its lower end, said annulus having a circumferential series of openings adjacent the upper edge thereof, a gas supply pipe connected with said annulus, a valve in said pipe, a second pipe supported by the annulus and establishing communication between the annulus and said tube, a perforated cap associated with said second mentioned pipe, and a valve for controlling the opening at one end of the tube.

2. A gas burner comprising a hollow body 70 open at both ends and constituting an air tube and mixing chamber, means for supporting said tube vertically, a hollow annulus removably fitted within the tube adjacent its lower end, a gas supply pipe connected with said tube, means carried by the tube and bearing against the annulus for supporting the annulus in said tube, said annulus having a circumferential series of openings, a second pipe supported by the annulus and establishing communication therebetween and said tube, a perforated cap associated with the second mentioned pipe, and a valve for controlling the opening at one end of the tube.

3. A gas burner comprising a hollow body open at both ends and constituting an air tube and mixing chamber, means for supporting said tube vertically, a hollow annulus fitted within said tube adjacent its lower end, said annulus having a circumferential series of openings adjacent the upper edge thereof, a gas supply pipe connected with said annulus, a valve in said pipe, a second pipe projecting horizontally from said annulus and having a vertically disposed portion, a perforated cap associated with said vertically disposed portion with the perforations arranged to direct the streams of gas in said pipe against the annulus below said openings therein, and a valve for controlling the opening at one end of the tube.

In testimony whereof I affix my signature.

JOHN HICKS.
